US00D650295S

(12) **United States Design Patent**
Schmitz et al.

(10) **Patent No.:** US D650,295 S
(45) **Date of Patent:** ** Dec. 13, 2011

(54) **BLISTER PACK FOR PHARMACEUTICALS**

(75) Inventors: Ursula Schmitz, Cologne (DE);
Thomas Groeziinger, Hamburg (DE)

(73) Assignee: AvidiaMed GmbH, Hamburg (DE)

(**) Term: **14 Years**

(21) Appl. No.: **29/347,756**

(22) Filed: **May 13, 2010**

(30) **Foreign Application Priority Data**

(57) **CLAIM**

The ornamental design for a blister pack for pharmaceuticals, as shown and described.

DESCRIPTION

FIG 1 is a front-left-top perspective view of the of a blister pack for pharmaceuticals showing our new design;

FIG. 2 is a view from the top side thereof;

FIG. 3 is a rear-right-bottom perspective view thereof; and,

FIG. 4 is a view from the bottom side thereof.

The broken line portion of the figure drawings is included to show unclaimed subject matter only and forms no part of the claimed design. The stipple shading indicates color contrast.
